PATENTED JULY 2, 1907.

P. J. HEDLUND.
STEAM TURBINE.
APPLICATION FILED JUNE 13, 1903.

Fig. 2.

UNITED STATES PATENT OFFICE.

PER JOHAN HEDLUND, OF STOCKHOLM, SWEDEN.

STEAM-TURBINE.

No. 858,869.

Specification of Letters Patent.

Patented July 2, 1907.

Application filed June 13, 1903. Serial No. 161,326.

To all whom it may concern:

Be it known that I, PER JOHAN HEDLUND, of Stockholm, Sweden, have invented a new and useful Improvement in Steam-Turbines, of which the following is a specification.

The invention relates to an elastic fluid turbine and consists more particularly in the conformation of the working passages and partition channels in which the buckets are disposed.

10 In the accompanying drawings Figure 1 is a vertical longitudinal section of my improved compound turbine, showing one unit and part of another together with the intermediate fixed guide channels. Fig. 2 is a horizontal section showing the disposition of the 15 wheel buckets and guide blades, other parts being omitted for clearness.

Similar numbers of reference indicate like parts.

1 is a wheel shaft. 2 the wheel casing shown cut away at 3, and 4 the working fluid inlet. On the 20 shaft 1 are fixed any desired number of wheels each forming a unit in the compounded series. Thus a wheel is shown at 5, and part of the next wheel at 6, the remainder of this wheel being cut away. Between successive wheels of the series are interposed fixed 25 partitions, as shown at 8 through which partitions the shaft 2 passes. In each wheel near the circumference is an annular working passage, the width of which measured radially the wheel increases from the inlet side 11 to the point 12 and then contracts to the outlet 30 13. In the fixed partitions 8 are similar annular channels 10 which also increase in width (similarly measured) from the inlet side 14 to the point 15 and then contract to the outlet 16.

In the annular working passage 9 are disposed the 35 wheel buckets (only three of which are here shown) 17, 18, 19, Fig. 2. Each of these buckets is curved at 20, this curved portion being situated at the widest place of the annular passage 9—or, as here shown, at the point 12. The parallel straight walls of the buck- 40 ets on the inlet side are longer than the parallel straight walls on the outlet side.

In the annular channel 10 of the fixed partition 8 are guide blades (only three of which are here shown) 21, 22, 23. Each of these guide blades is curved at 45 24, the curved portion being situated at the widest place of the annular channel 10—or as here shown at the point 15. The direction of curvature of the guide blades 21, 22, 23 is the reverse of that of the wheel buckets 17, 18, 19. The parallel straight walls of said 50 guide blades on the inlet side are longer than the parallel straight walls on the outlet side.

The width radially measured of each wheel outlet 13 is greater than the width of the inlet of 11. The width of the inlet 14 of the channel 10 in each fixed partition 55 may be equal to the width of the outlet 13 of the wheel located on the pressure side thereof, and the width of

the outlet 16 of said channel may be equal to the width of the inlet of the wheel located on the exhaust side thereof.

The working fluid inlet 4 is annular and is contracted in width radially the wheels as shown at 25. The width of the delivery opening 26 may be equal to the width of the inlet 11 of wheel 5. In the contracted portion of said annular inlet are disposed inclined parallel guide blades, three of which are represented at 27, 28, 29. The working fluid entering at 4 passes as indicated by the arrows 7 between the guide blades 27, 28, 29, then to the buckets 17, 18, 19 in the working passage of wheel 5—so rotating said wheel,—and then to the guide blades 21, 22, 23 in the channel in 70 partition 8, then to the buckets in the working passage of the next wheel, and so on until the final exhaust is reached.

By reason of the contraction of the inlet the velocity of the incoming fluid is increased so that it strikes the 75 buckets of wheel 5 with increased momentum. By reason of the enlargement of the working passage 9 from the inlet to the point 12 the velocity of the fluid doing work on the wheel becomes converted into pressure. The fluid expands while escaping from the outlets 13. 80 Hence said fluid acts upon the wheel both by impact and by reaction, and causes the wheel to rotate in the direction of the arrow a. From wheel 5 the fluid passes to channel 10 and between guide blades 21, 22, 23, and by reason of the increase in width of said channel its velocity of exhaust from wheel 5 is converted into pressure. Expanding again it enters wheel 6, upon the buckets of which and in the working passages of which it acts in the same way as already described in connection with wheel 5. 85

The velocity of the working fluid before reaching the inlet of each successive wheel is, by the foregoing construction, brought to a maximum, while within the working passage and intermediate channels its pressure is brought to a maximum. In this way a desirable 90 economy of operation is obtained.

I claim:

1. An elastic fluid turbine of the axial flow type provided with an annular working passage expanding from the opening in the side of the partition or wheel to the place of greatest width and contracting from said place of greatest width to the delivery opening in said partition or wheel. 100

2. An elastic fluid turbine of the axial flow type having an annular working passage and buckets disposed therein, the said passage increasing in width measured radially the wheel to a point nearer to the outlet than to the inlet and then decreasing in width to said outlet. 105

3. The combination of an elastic fluid turbine of the axial flow type having an annular working passage and buckets disposed therein; the said passage having a contracted inlet and a contracted outlet, and a casing having a fixed partition parallel to the exhaust side of said wheel provided with an annular channel having a contracted inlet and a contracted outlet and guide blades in said 110 115

channel; the inlet of said channel registering with the outlet of said working passage.

4. In combination with an elastic fluid turbine of the axial flow type having an annular working passage provided with a contracted inlet and a contracted outlet, parallel buckets disposed in said passage, each of said buckets being curved with the apex of curvature nearer to the outlet than to the inlet of the said working passage.

5. In combination with an elastic fluid turbine of the axial flow type having an annular working passage provided with a contracted inlet and a contracted outlet, parallel buckets disposed in said passage: each of said buckets having straight walls connected by a curved portion, the apex of curvature being nearer to the outlet than to the inlet side of said working passage.

6. The combination of an elastic fluid turbine of the axial flow type, having an annular working passage provided with a contracted inlet and a contracted outlet, and a casing having a fixed partition parallel to the exhaust side of said wheel provided with an annular channel having a contracted inlet and a contracted outlet; the inlet of said channel registering with the outlet of said working passage, buckets in said working passage and guide blades in said channel: each of said buckets and guide blades being curved with the apex of curvature nearer to the outlet than to the inlet of the respective passage or channel.

7. An elastic fluid turbine of the axial flow type having an annular working passage constricted at both extremities.

8. An elastic fluid turbine of the axial flow type having an annular working passage constricted at both ex-

tremities in combination with a casing having a fixed partition parallel to said turbine and provided with an annular channel constricted at one extremity; the constricted extremity of said channel registering with one extremity of said working passage.

9. An elastic fluid turbine of the axial flow type having an annular working passage constricted at both extremities in combination with a casing having a fixed partition parallel to said turbine and provided with an annular channel constricted at both extremities: an extremity of said channel registering with one extremity of said working passage.

10. Two elastic fluid turbines of the axial flow type, each having an annular working passage constricted at both extremities, a casing, and in said casing, interposed between said turbines, a fixed partition having an annular channel constricted at both extremities: the extremities of said channel registering with the adjacent extremities of the working passages.

11. An elastic fluid turbine of the axial flow type having an annular working passage constricted at both extremities, a casing, and in said casing two fixed partitions disposed on opposite sides of said turbine and each having an annular channel constricted at both extremities: the extremities of said working passage registering with the adjacent extremities of the said channels.

In testimony whereof I have signed my name to this specification in the presence of two subscribing witnesses.

PER JOHAN HEDLUND.
